US0D1097933S

(12) **United States Design Patent** (10) **Patent No.:** **US D1,097,933 S**
(45) **Date of Patent:** **** Oct. 14, 2025**

(54) **MUDFLAP**

(71) Applicant: **CATERPILLAR SARL**, Geneva (CH)

(72) Inventors: **Andrew Crawford**, Durham (GB);
Udhayanan Annamalai, Chennai (IN)

(73) Assignee: **CATERPILLAR SARL**, Geneva (CH)

(**) Term: **15 Years**

(21) Appl. No.: **29/922,539**

(22) Filed: **Dec. 22, 2023**

Related U.S. Application Data

(63) Continuation of application No. 29/808,716, filed on Sep. 22, 2021, now Pat. No. Des. 1,015,243.

(57) **CLAIM**

The ornamental design for a mudflap as shown and described.

DESCRIPTION

FIG. 1 is a top, front and left side perspective view of a mudflap showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines depict portions of the mudflap which form no part of the claimed design.

1 Claim, 5 Drawing Sheets
